CLAIM

The ornamental design for an ear pain relief device as shown and described.

DESCRIPTION

FIG. 1 is a front, right, top perspective view of an ear pain relief device showing our new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof; and,

FIG. 9 is an alternate configuration shown with a cover installed.

The broken lines shown on the drawings depict portions of the ear pain relief device that form no part of the claimed design.

1 Claim, 8 Drawing Sheets
